UNITED STATES PATENT OFFICE

2,507,342

TOOTHBRUSH HOLDER

Vincent Licari and Anthony F. Licari,
Brooklyn, N. Y.

Application April 30, 1947, Serial No. 744,864

9 Claims. (Cl. 312—112.5)

1

This invention relates to tooth brush holder, and the object of the same is to provide a simple holder which may be readily closed or opened by a movement of a tooth brush corresponding to that necessary to enclose a tooth brush or to remove a tooth brush.

The invention consists of a casing having parts hinged along a pintle and having horizontal members each pivoted to a supporting wall with a spring connecting the pivots, the opening of the casing moving the pintle axis to the front of the spring and the closing of the casing moving the pintle axis to the rear of the spring, the horizontal members having cutouts for the neck of the tooth brush shaped to cause closing of the casing by the movement of the tooth brush in one direction and to cause opening of the casing by the movement of the tooth brush in the other direction.

Suitable features are added to provide efficient operation.

The invention will be more fully described hereinafter, embodiments thereof shown in the drawings, and the invention will be finally pointed out in the claims.

In the accompanying drawings:

Fig. 1 is a perspective front view of the improved brush holder;

Fig. 2 is a front view of the same in closed position;

Fig. 3 is a side view of Fig. 2;

Fig. 4 is a rear view of Fig. 2;

Fig. 5 is a top view of Fig. 2;

Fig. 6 is a bottom view of Fig. 2;

Fig. 7 is a bottom view of Fig. 2, but in open position;

Fig. 8 is a perspective view of the supporting plate, and

Fig. 9 is a detail view of a guide pin.

Similar characters of reference indicate corresponding parts throughout the various views.

Referring to the drawings, the supporting bracket 10 is of angular shape, with a vertical back portion 11 having openings 12, for nails, screws or the like to support the member 10 to a wall. The horizontal portion 13 has a central cutout 14 forming two legs, and an elongated slot 15 in each leg. Each of the slots 15 extends through the horizontal portion 13, for the passage of guide rods 16, one secured to each of the base portions 20 of a casing 21.

This casing 21 consists of two leaves, 22 and 23 hinged at 24. Alternating knuckles 25 and recesses 26 are provided and the knuckles 25 are superposed on each other. A pintle 26a passes

2

through openings in the knuckles. The base portions 20 have each a cutout 30, each of a depth about one half of the width of a neck portion of a tooth brush and of a width about the depth of the neck of a standard tooth brush (shown in dotted lines in side view in Fig. 3 where the depth is shown). Also each base portion 20 has a projection 31, one overlapping the other, to act as an abutment to serve to limit the closing of the leaves 22 and 23, and to provide means to be pushed by the tooth brush to close the leaves. The bottom of the base plates 20, have recesses 33. The guide pins 16 extend from the base plates 20 to which they are fastened downwardly through the elongated slots 15 in the horizontal portion 13 of the bracket 10.

Each of these pins 16 is connected with one end of a helical spring 40. The pins 16 are connected with the rear of the base portions 20, which extend to the rear of the axis of the pintle 26a, when the leaves 22 and 23 of the casing 21 are open, as shown in Fig. 7, but which rear portions of the base portions are to the front of the axis of the pintle 26a, when the leaves are closed, as shown in Fig. 6. The spring 40 takes a corresponding position, once in the front of the axis of the pintle 26a as in Fig. 6, and once in the rear of the axis pintle as in Fig. 7. There is toggle action in respect to the axis pintle.

From this structure, the operation is as follows: A brush is placed into the mouth of the open jaws or leaves 22 and 23, and is pressed against the projections 31 whereby the jaws close to enclose the tooth brush and remain closed due to the toggle action of the spring 40, the pins 16 moving in the slots 15. When it is desired to remove the tooth brush, it is pressed outwardly and the jaws or leaves thereby open, and due to the toggle action remain open, until the projections 31 are again pressed by the insertion of a tooth brush.

The casing when enclosing a tooth brush, keeps dust and germs from the bristles, at the same time allowing a satisfactory drainage.

We have described several forms of our invention, but obviously various changes may be made in the details disclosed without departing from the spirit of the invention as set out in the following claims.

50 We claim:

1. A tooth brush holder, comprising an angular bracket having a horizontal part with a pair of elongated slots, a pair of hinged leaves forming a bristle end enclosing casing, each leaf having a horizontal plate with a guide pin passing

through an elongated slot, and a spring having each end secured to a guide pin, whereby the spring tends to hold the leaves open or closed.

2. A tooth brush holder, comprising an angular bracket having a horizontal part with a pair of elongated slots, a pair of hinged leaves forming a bristle end enclosing casing, each leaf having a horizontal plate with a guide pin passing through an elongated slot, and a spring having each end secured to a guide pin, said hinge being in front of the guide pins when the leaves are open and at the rear of the guide pins when the leaves are closed, whereby the spring tends to hold the leaves open or closed.

3. A tooth brush holder, comprising an angular bracket having a horizontal part with a pair of elongated slots, a pair of hinged leaves forming a bristle end enclosing casing, each leaf having a horizontal plate with a guide pin passing through an elongated slot, and a spring having each end secured to a guide pin, each of said horizontal plates having a recess of the depth and width of a neck of a standard tooth brush, whereby the spring tends to hold the leaves open or closed.

4. A tooth brush holder, comprising an angular bracket having a horizontal part with a pair of elongated slots, a pair of hinged leaves forming a bristle end enclosing casing, each leaf having a horizontal plate with a guide pin passing through an elongated slot, and a spring having each end secured to a guide pin, each of said horizontal plates having a recess of the depth and width of a neck of a standard tooth brush, whereby the spring tends to hold the leaves open or closed, and each of the horizontal plates having a recess at its rear for the passage of the spring.

5. A tooth brush holder, comprising an angular bracket having a horizontal part with a pair of elongated slots, a pair of hinged leaves forming a bristle end enclosing casing, each leaf having a horizontal plate with a guide pin passing through an elongated slot, and a spring having each end secured to a guide pin, each of said horizontal plates having a recess of the depth and width of a neck of a standard tooth brush, whereby the spring tends to hold the leaves open or closed, each of the horizontal plates having a recess at its rear for the passage of the spring, and each of said horizontal plates having a projection in front of the axis of the hinge, to limit the closing movement of the leaves, and to open the leaves on pressure being applied.

6. A tooth brush holder, comprising an angular bracket having a horizontal part with a pair of elongated slots, a pair of hinged leaves forming a bristle end enclosing casing, each leaf having a horizontal plate with a guide pin passing through an elongated slot, and a spring having each end secured to a guide pin, each of said horizontal plates having a recess of the depth and width of a neck of a standard tooth brush, whereby the spring tends to hold the leaves open or closed, each of the horizontal plates having a recess at its rear for the passage of the spring,

and each of said horizontal plates having a projection in front of the axis of the hinge, to limit the closing movement of the leaves, and to open the leaves on pressure being applied, said horizontal part of the bracket having a central cutout.

7. In a tooth brush holder, the combination of a horizontal support adapted to be placed on a wall, and having a pair of slots and a cutout centrally of the slots for the passage of the brush handle, and a casing including a pair of door like members hinged at their vertical rear ends and having bottom plates each with a cutout, which, when the plates abut, form a recess of substantially the depth and width of a neck of a standard tooth brush, to support the bristle end within the casing, a pin extending from the lower side of each bottom plate and each pin detachably engaging one of the slots and smaller in diameter than the length of the slot, whereby the casing may be detached from the support for cleaning and replaced on the support by merely inserting the pins in the slots and resting the casing on the support.

8. In a tooth brush holder, the combination of two like members of a height at least higher than the bristle end of a standard tooth brush, and when abutting forming a casing, each rear end hinged to the other to enable the casing to be opened at the front end of the members, each member having a bottom plate, each plate with a cutout between the hinge axis and the front of the casing, the two cutouts forming a recess when the casing is closed, the recess having a depth and width substantially equal to the depth and width of the neck of a standard tooth brush to support the bristle end of the toothbrush within the casing, overlapping projections at the inner part of the recess, which, when the casing is open, are inclined to each other, and adapted to be brought into alignment when pressed by the incoming neck of the tooth brush, the movement of the projections to aligned position moving the members to close the casing.

9. In a tooth brush holder, the combination with an angular bracket having a horizontal part with a pair of elongated slots of a pair of hinged leaves forming a bristle end enclosing casing, each leaf having a horizontal plate with a guide pin above a slot in the horizontal part of the bracket extending from the bottom of the horizontal plate of the casing and passing through said elongated slot.
